The ornamental design for a set of capsules and case therefor for teaching the periodic table of elements, as shown and described.

DESCRIPTION

FIG. 1 is a front perspective view of a set of capsules and case therefor for teaching the periodic table of elements showing my new design with the case closed;

FIG. 2 is a front perspective view thereof with the case opened;

FIG. 3 is a front elevational view thereof with the case closed;

FIG. 4 is a bottom plan view thereof with the case closed;

FIG. 5 is a top plan view thereof with the case closed;

FIG. 6 is a rear elevational view thereof with the case closed;

FIG. 7 is a left side elevational view thereof with the case closed, the right side elevational view thereof being a mirror image and, therefore, not being shown;

FIG. 8 is a front perspective view of an individual capsule thereof;

FIG. 9 is a front perspective view thereof with the case opened and with all the capsules removed therefrom;

FIG. 10 is a sectional view taken along line 10—10 in FIG. 2 showing a portion of the case with the capsules therein; and,

FIG. 11 is a top plan view showing the case in opened condition.
